PREPARATION OF CHLORPHENOXY ACETONITRILES

Harry James Barber and Maurice Berkeley Green, Dagenham, England, assignors to May & Baker Limited, Dagenham, England, a British company

No Drawing. Application December 3, 1951,
Serial No. 259,716

Claims priority, application Great Britain
December 6, 1950

8 Claims. (Cl. 260—465)

This invention is for improvements in or relating to the production of chlorphenoxy compounds, in particular chlorphenoxyacetonitriles and to the production therefrom of chlorphenoxyacetic acids and their derivatives.

Chlorphenoxyacetonitriles, especially the 2:4-dichloro compound, were hitherto available only from the corresponding substituted acetic acid, or were formed by the interaction of the corresponding phenol and chloracetonitrile, the latter compound being prepared from chloracetic

5 pounds) are of considerable importance as plant growth regulators and selective herbicides.

Conversion of the chlorphenoxyethyl chloride in chlorphenoxyacetonitrile by metathetical reaction with an alkali metal cyanide must, as hereinbefore mentioned, be effected in a solvent medium which consists at least predominately of a ketonic solvent with a minor proportion of water if a satisfactory yield is to be obtained. The amount of water employed should be the minimal quantity required to keep the alkali metal cyanide in solution; less water is required, and in consequence a higher yield obtained, in the case of sodium cyanide which is, therefore, the preferred cyanide. The results of some of the experiments carried out for the purpose of determining the conditions necessary for obtaining a satisfactory yield 10 of the nitrile in the case of the conversion of 2:4-dichlorophenoxyethyl chloride to 2:4-dichlorophenoxyacetonitrile are shown in the following table in which is set out the conditions of reaction and the percentage by weight of nitrile obtained. It is evident from this table that the solvent conditions employed in accordance with the invention as compared to the other reaction conditions noted in the table ensure a spectacular increase in yield 15 of the desired nitrile.

TABLE

Expt. No.	Cyanide	Solvent	Temp., degrees	Time (Hours)	2:4-Dichlorophenoxyacetonitrile
1	KCN, 1.1 moles	Dry methanol	20	24	25%
2	KCN, 1.1 moles	Dry acetone	20	24	very little.
3	KCN, 2.0 moles	Dry methanol	65	2 ¹ / ₂	15%
4	KCN, 2.0 moles	Glycerol	90-95	2	intractable tarry product.
5	KCN, 2.0 moles	Acetone+water	60	2 ¹ / ₂	65%
6	KCN, 2.0 moles	Acetone+water buffered to pH7.	60	2 ¹ / ₂	63%
7	KCN, 2.0 moles	MEK ¹ +water	60	2 ¹ / ₂	71%
8	NaCN, 1.0 mole	Acetone+water	60	2 ¹ / ₂	70%
9	NaCN, 2.0 moles	do	60	2 ¹ / ₂	70%
10	KCN, 2.0 moles	Dioxan+a little water	80-85	2	82%
11	KCN, 2.0 moles	do	80-85	5 ¹ / ₂	24%

¹ MEK=methyl ethyl ketone.

acid by the classical sequence of operations to convert the carboxy group into a cyano group i. e. via an ester and amide.

It is the object of the present invention to provide an improved, more specifically a more economic, method of preparing the said nitriles such as to render them convenient intermediates not only for the production of those derivatives of the corresponding substituted acetic acids which cannot easily be obtained from the acids themselves but also for the production of the acids and derivatives of the type of the esters and salts.

It has been unexpectedly found that chloranisoles obtainable by the chlorination of anisole under conditions favouring nuclear chlorination can be employed as starting materials for the production of the required nitriles and, provided that various operating conditions herein-after referred to are observed, that the overall process offers decided commercial advantage over the hitherto known processes for producing the said nitriles.

In accordance with the present invention, a chlorphenoxyethyl monochloride is reacted with an alkali metal cyanide, preferably potassium or sodium cyanide, in a solvent medium consisting predominately of a ketonic solvent and containing a minor proportion of water.

Production of 4-chlor-, 2:4-dichlor- and 2:4:6-trichlorophenoxyacetonitriles in this way followed by alkaline hydrolysis or alcoholysis represents a particularly favourable method of manufacture of the corresponding chlorphenoxyacetic acids and esters respectively as compared with the methods hitherto employed for producing these compounds which (especially the 2:4-dichlor com-

45 If the resulting nitrile is required as a source of the corresponding acid or esters, it is not necessary first to isolate the nitrile from the crude reaction product containing it. Thus the crude reaction product may be subjected to hydrolysis or alcoholysis direct by treatment at elevated temperature with aqueous alkali or with alcohol in the presence of an acid esterification catalyst respectively.

50 The process of the present invention is illustrated by the following examples:

Example I

Anisole (108 g.) is chlorinated at a temperature not exceeding 100° C. until the weight has increased by 69 g. 55 Phosphorus pentachloride (10.5 g.) is added and chlorination is continued at 190-200° C. until the weight has increased by a further 34.5 g. Carbon dioxide is passed through to remove hydrogen chloride and excess chlorine, and the yellow oily product is poured into ice and water, extracted with ether and the ether extract washed twice with ice-cold N caustic soda solution, then twice with ice-water and finally dried over anhydrous magnesium sulphate. The ether is evaporated off and the residual oil is dissolved in 500 cc. acetone.

60 This solution is added gradually over a period of two hours to a vigorously stirred mixture of 400 cc. acetone and a solution of potassium cyanide (130 g.) in water (300 cc.) heated to 65° C. The resulting dark brown solution is heated under reflux for one hour at 80° C. then 65 poured into a mixture of ice-water (3000 cc.) and 2N caustic soda solution (500 cc.). An oil separates which

solidifies on standing and is filtered off, washed with water and pressed as dry as possible.

This solid is boiled under reflux for two hours with 25% w./v. caustic soda solution (1000 cc.), the mixture is then cooled in ice and the solid is filtered off, washed with successive small amounts of ice-water and pressed as dry as possible. It is then redissolved in boiling water (4000 cc.). An insoluble oil remains which solidifies on cooling to 80° C. and is filtered off at that temperature, washed with warm water and dried, giving bis-(2:4-dichlorphenoxy)-methane (42 g.) M. P. 98-100° C. The filtrate is treated with charcoal, filtered hot and made acid to Congo red with hydrochloric acid. The precipitated solid is filtered off, washed with water and dried, giving 2:4-dichlorphenoxyacetic acid (132 g.), M. P. 140-142° C. in 60% yield.

Example II

A solution of 38.5 g. of sodium cyanide in 57.5 cc. of hot water is added to 192 cc. of acetone stirred at 60° C. A solution of 81.2 g. of crude 2:4-dichlorphenoxymethyl chloride in 192 cc. of acetone is added drop-wise during one hour, with vigorous stirring. The brown mixture is refluxed for two hours then poured into a mixture of 1.15 litres of ice-water and 192 cc. of 2N caustic soda solution. The solid is filtered off, washed with water and pressed dry.

The solid is boiled under reflux for two hours with 385 cc. of 25% w./v. caustic soda solution and the mixture cooled somewhat and the solid filtered off, washed with hot water and dried, giving 11.2 g. of bis-(2:4-dichlorphenoxy)-methane. The filtrate is acidified to Congo red and the solid filtered off, washed with water and dried, giving 72 g. of 2:4-dichlorphenoxy acetic acid, M. P. 140-142° C.

Example III

4-chlorphenoxyethyl chloride, M. P. 105-115° C., 15 mm., M. P. 29-30° C. is converted into the corresponding nitrile and thence into the corresponding acid in analogous manner to that described in Example II.

We claim:

1. A process for the preparation of a chlorphenoxy-acetonitrile which comprises reacting a chlorphenoxy-methyl mono-chloride with an alkali metal cyanide in a solvent medium consisting of a ketonic solvent and a minor proportion of water.
  2. A process according to claim 1 in which the ketonic solvent is acetone.
  3. A process according to claim 1 in which the ketonic solvent is methyl ethyl ketone.
  4. A process for producing 2:4-dichlorphenoxyacetonitrile which comprises reacting 2:4-dichlorphenoxyethyl chloride with an alkali metal cyanide in a solvent medium consisting of a ketonic solvent and a minor proportion of water.
  5. A process for the preparation of a chlorphenoxyacetonitrile which comprises reacting a chlorphenoxyethyl mono-chloride with sodium cyanide in a solvent medium consisting of a ketonic solvent and a minor proportion of water.
  6. A process according to claim 5 in which the ketonic solvent is acetone.
  7. A process according to claim 5 in which the ketonic solvent is methyl ethyl ketone.
  8. A process for producing 2:4-dichlorphenoxyacetonitrile which comprises reacting 2:4-dichlorphenoxyethyl chloride with sodium cyanide in a solvent medium consisting of a ketonic solvent and a minor proportion of water.
